United States Patent Office.

JOHN BROWN ALDEN, OF WORCESTER, MASSACHUSETTS, ASSIGNOR TO
HIMSELF AND EDWIN C. CLEVELAND, OF SAME PLACE.

Letters Patent No. 62,987, dated March 19, 1867.

IMPROVED BRUSH.

The Schedule referred to in these Letters Patent and making part of the same.

TO ALL WHOM IT MAY CONCERN:

Be it known that I, JOHN BROWN ALDEN, of Worcester, in the county of Worcester, and State of Massachusetts, have invented a new and useful improvement in Brushes; and I do hereby declare that the following is a full, clear, and exact description thereof, which will enable others skilled in the art to make and use the same, reference being had to the accompanying drawings, forming part of this specification.

This invention relates to the manner in which the stalk of the brush is constructed, and it consists in making the body of the stalk of the brush in two pieces, which are pivoted together, whereby the brush can be reversed or changed end for end, as will hereinafter appear.

Figure 1 represents the brush as it appears when ready for use.

Figure 2 represents the brush partly reversed.

Similar letters of reference indicate like parts.

A represents the brush attached to a piece of wood, B, or other material, in the usual manner, and which piece forms a part of the stalk. C is the other part of the stalk, and D is the handle of the brush. E is a pivot, (or a screw which forms a pivot,) which passes through C, and upon which the piece B or the brush turns. The two pieces B C are held together by the pivot E, and by a screw or pin, a, which is inserted to prevent the brush from turning when it is in use. When the outer end of the brush becomes worn and useless the screw a is withdrawn, when the brush can be reversed or turned round and the other end used, thus making the brush about twice as durable as it otherwise would be.

Having thus described my invention, what I claim as new, and desire to secure by Letters Patent, is—

The arrangement and combination of the parts of the brush marked A B and C, whereby the parts A B may be reversed or turned end for end, substantially as described for the purposes herein set forth.

The above specification of my invention signed by me this 14th day of December, 1866.

JOHN BROWN ALDEN.
